BUST DEVELOPING DEVICE

Filed Aug. 9, 1929

INVENTOR
Peggy Brown
BY Colleen A. Blachly
ATTORNEY

UNITED STATES PATENT OFFICE

PEGGY BROWN, OF GREENWICH, CONNECTICUT

BUST-DEVELOPING DEVICE

Application filed August 9, 1929. Serial No. 384,596.

This invention relates to new and useful improvements in bust massagers and is particularly intended for developing the busts and is also beneficial after child birth in case the breast milk becomes sour, for massaging away the lumps formed in the milk of the breast.

The invention has for an object the provision of a device of the class mentioned which is of simple, durable construction, dependable in use and efficient in action, and which can be manufactured and sold at a reasonable cost.

The invention proposes a vibrator connected with a pair of oppositely extending horizontal adjustable arms supporting bust cups at their ends, and arranged to vibrate in both the vertical and the horizontal, said vibrator being connected with the shaft of a motor adjustably mounted upon a stand.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a side elevational view of a device constructed according to this invention, during use.

Fig. 2 is an enlarged fragmentary detailed side elevational view of the device, per se.

Fig. 3 is an end elevational view looking in the direction of the arrows 3—3 of Fig. 2.

Fig. 4 is a sectional view taken on the line 4—4 of Fig. 5.

Fig. 5 is a plan view of the device.

Fig. 6 is a sectional view taken on the line 6—6 of Fig. 4.

Fig. 7 is a sectional view taken on the line 7—7 of Fig. 4.

Fig. 8 is an enlarged detailed sectional view taken on the line 8—8 of Fig. 3.

Fig. 9 is a view similar to Fig. 8 but illustrating a modification.

Fig. 10 is a similar view to Fig. 6 showing a modified form of gear drive.

The reference numeral 10 indicates gener-

ally a base plate provided with a vertical boss 11 supporting a vertical rod 12. A motor bracket 13 is slidably mounted upon the rod and held in fixed adjusted positions by a set screw 14 threadedly engaging thru the bracket and abutting the rod. A motor 15 is mounted upon the bracket 13 and connects with an extendible shaft 16 consisting of two sections interengaging, and held in extended adjusted positions by a set screw 17 threadedly engaged in one of the sections and abutting the other. A cable 18 connects with the motor and is connectible with a plug 19 of an electric circuit.

A vibrator 20 is supported upon the free end of the extendible shaft 16 and held from rotation by a pair of pins 15' slidably engaging in sockets formed in rearwardly projecting extensions 20' and is provided with a rubber front cap 21 engageable against the chest of a person during use. The rubber cap 21 is spaced from the casing 28 by suitable washers 21'. A pair of oppositely extended arms 23 project from the opposite sides of the vibrator and support bust cups 24. These arms are adjustable in length and each consists of two sections interengaged and held in fixed positions by a set screw 25 threadedly engaging one of the sections and abutting the other. The bust cups 24 are attached at one corner as illustrated in Fig. 8 upon the free end of the arm 23 by a bolt 26, and a curved flat spring 27 has one of its ends held fixed by the bolt while the other end engages against the side of the bust cup and holds it at an angular position. In Fig. 5 the springs 27 may be clearly seen holding each of the bust cups in the angular position just referred to.

The vibrator 20 consists of a casing 28 supported by the said shaft 16. The shaft 16 extends into the casing and carrying a small gear 35. A second small gear 36 is rotatively supported within the casing and meshes with the gear 35. A large gear 37 meshes with the gear 36, and a second large gear 38 meshes with the gear 35.

The said arms 23 are pivotally attached on their inner ends eccentrically on the gears 37 and 38 as may be seen in Fig. 4. These arms

slidably pass thru collars 39 pivotally supported within the casing, and pass thru apertures in the side of the casing.

In Fig. 1, a chair 40 has been shown arranged upon the base plate 10 and a woman 41 sitting on the chair and using the vibrator. In operation of the vibrator the electric motor is started rotating the shaft 16 and transmitting this rotation to the gears 37 and 38.

10 As these gears turn, the arms 23 will be moved simultaneously outwards and inwards and simultaneously upwards and downwards. For changing the height of the device the set screw 14 may be loosened and the bracket 13 moved up or down upon the bar 12. The distance between the bust cups may be changed by loosening the set screws 25 and extending or retracting the sections of the arms 23. Preferably the bust cups should be made of 20 rubber.

25 In the modified form of the device illustrated in Fig. 9, the outer end of each of the arms 23 is formed with a hinge 42 arranged to pivot in the horizontal. A wing set screw 43 engages this hinge and serves to lock the hinge in various angular adjusted positions. This arrangement permits an adjustment of the angularly inclined positions of the bust cups.

30 In the form shown in Fig. 10, the shaft extends into the casing 28' and has worm 29 on its inner end. This worm meshes with a worm wheel 30 on a shaft 31 rotatively mounted within the casing and provided with 35 a bevel gear 32. A second bevel gear 33 meshes with the said bevel gear and is fixed upon a shaft 34 rotatively mounted within the casing and carrying the said small gear 35 which in turn is connected with gears 36 and 40 38 as above described. By means of this gear drive the bust is massaged at a lower rate.

45 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what 50 I claim as new, and desire to secure by United States Letters Patent is:—

1. A bust massager, comprising a motor, a stand for supporting the motor at adjusted heights, an extendible shaft connected with 55 the motor, a vibrator mounted on the end of the shaft, extendible vibration arms projecting from the vibrator, and bust cups pivotally attached on the free ends of the arms, springs supported on the ends of the arms and 60 freely engaging against the sides of said cups for holding the cups in a fixed converging angular position.

2. In a device of the class described, a vibrator casing for suspension on the end of a 65 motor shaft, a speed reduction within the cas-

ing and connectible with said shaft, a pair of small meshing gears within the casing and one of said pair being connected with the speed reduction, a pair of gears meshing with said small gears respectively, arms extending thru opposite ends of the casing and at their inner ends respectively pivotally connected with the second pair of gears, collars freely holding said arms and pivotally mounted, bust cups pivotally mounted on the free ends of the arms, and means for holding the cups in a fixed converging angular position.

3. In a device of the class described, a vibrator casing for suspension on the end of a motor shaft, a speed reduction within the casing and connectible with said shaft, a pair of small meshing gears within the casing and one of said pair being connected with the speed reduction, a pair of gears meshing with said small gears respectively, arms extending thru opposite ends of the casing and at their inner ends respectively pivotally connected with the second pair of gears, collars freely holding said arms and pivotally mounted, and bust cups on the free ends of the arms, each of said arms being formed with a horizontal hinge, and a wing screw for clamping the hinge in fixed positions for angularly adjusting the bust cup.

In testimony whereof, I have affixed my signature.

PEGGY BROWN.
